UNITED STATES PATENT OFFICE.

DONALD McDONALD, OF LOUISVILLE, KENTUCKY.

REINFORCING-BAR FOR CONCRETE.

1,052,683.

Specification of Letters Patent. Patented Feb. 11, 1913.

Application filed June 21, 1912. Serial No. 705,145.

To all whom it may concern:

Be it known that I, DONALD McDONALD, a citizen of the United States, residing at Louisville, in the county of Jefferson and 5 State of Kentucky, have invented certain new and useful Improvements in Reinforcing-Bars for Concrete, of which the following is a specification.

The object of my invention is to provide 10 a reinforce for concrete construction comprising a series of bars, each bar being formed with projections constructed to interlock with similar projections on another bar, and fastenings securing the bars together at their intersection.

In the drawing, Figure 1 is a longitudinal elevation of a bar embodying my invention; Fig. 2 is a longitudinal section of the same; Fig. 3 is a section on the line 3—3, 20 Fig. 1; Fig. 4 is a section on the line 4—4, Fig. 1; Figs. 5 and 6 are assembly views showing bars coupled together; Fig. 7 is a bottom plan view of one of the fastening means; Fig. 8 is a detail view showing the 25 triangles lightened; Fig. 9 is a detail view showing the triangular projections on one side of the bar only.

While the bar may be of any approved shape, I prefer to construct it as per the 30 cross-sectional views shown in Figs. 3 and 4, by rolling the metal through suitable rolls, so that the bar is completely formed in the process of rolling. It will be noted that the sides of the bar are beveled so as to clear 35 the rolls of the mill through which the bar is passed. The projections on the bar, to be hereinafter referred to, are also beveled on their edges for the same reason.

1 represents the bar on which are formed, 40 by the process of rolling, right angle triangles 2 and seats 3 and 4. The right angle triangles are arranged in pairs so as to provide the recess or seat 3 at right angles to the longitudinal axis of the bar, and the seat 45 4 at an oblique angle, for instance the angle at 45 degrees, to the longitudinal axis of the bar, so that the reinforce may be constructed by the use of these bars without bending or deflecting the bars. I prefer to construct the 50 projections as right angle triangles whose bases and altitudes are equal to the width of the bar, and to space them as shown in Fig. 1. It will be seen that by placing the companion bar in the seat 3, the two bars are 55 mortised together at right angles; by placing the companion bar in the seat 4, the bars

are secured together at an angle of 45 degrees, as shown in Fig. 6.

When the bars are fitted together in the desired position, they are prevented from 60 separating by any suitable device which will hold them together. They may be wrapped with wire, or a plate of iron may be placed on each side of the joint with two or more bolts holding the plates together on the 65 bars. I prefer to join the bars together at their intersection by means of clips 5, as shown in Fig. 7, said clips being provided with mortises 6 and 7 adapted to engage a corner of the right angle triangle projections 70 on the respective bars. These plates are provided with bolt openings 8, whereby they may be firmly clamped to the bars. By preventing the separation of the bars, and by properly proportioning the amount 75 of metal in the projections to the size of the bar, every joint can be made as strong, if not stronger, than the bar itself.

The four positions in which companion bars may be placed relative to each other, 80 as can be seen from the drawing, lend this particular construction of bar to a great many constructions. For instance, the frame of a structure can be set up and braced. A truss can be made of almost any 85 span, as the top chords and bottom chords can be built up of three or more bars to any length desired. Used as a concrete reinforcement, the projections on the bars furnish an excellent hold to prevent the bars 90 slipping in the concrete. They allow reinforcement at right angles or at any desired angle and permit the building up of truss rod reinforcement for concrete beams.

For the purpose of my invention, it is not 95 necessary to roll any special bar, but only to select bars of such size and in such number as to get the strength required in the bottom chord, and insert into them bars of proper length, proper size and proper number to make the angle members each project up from the bottom chord to the height desired.

The fastening clips shown in Fig. 7 can be rolled in one continuous strip and the 105 mortises 6 and 7 formed in the process of rolling, after which the clips are sheared the proper length.

By beveling the bars as shown in Figs. 3 and 4, I am enabled to have intermeshing 110 bars of varying thickness according to the strength desired. This plan results in bars

which will, as stated, mesh with each other, although one may be several times heavier than the other, inasmuch as the bevel on all the bars will be formed on the same angle.

- 5 The sides of the bar may be curved, if desired, including the edges of the projections on the bar. If desired, considerable metal may be taken out of the triangle, in which case the diagonally disposed edge of the triangle will serve as a tension member to prevent the bar pulling in two, and at the same time leave the projections with sufficient bearing strength and sufficient shearing strength to develop the full tensile strength 10 of the bar.

If preferred or found necessary, the bar may be formed with triangular projections on one side only, but in this case, I prefer to increase and balance the hold of the bar 20 in concrete, by forming ordinary corrugations on the opposite side of the bar, as shown in Fig. 9.

I claim:

1. A bar for reinforcing concrete formed 25 with right angle triangular projections reversely arranged in pairs, having the base

of each in alinement with one side of the bar and the inclined sides parallel to each other and inclined to the axis of the bar, the distance between any two projections being 30 the same width, whereby seats are formed on the bar at right and oblique angles to the longitudinal axis of the bar.

2. A bar for reinforcing concrete having one or more faces provided with a series of 35 right angle triangular projections; each projection arranged with its base in alinement with one side of the bar and its inclined side inclined to the axis of the bar, and every projection having its inclined side 40 parallel with the inclined side of an adjacent projection, and its third side which is at right angles to the longitudinal axis of the bar parallel with the corresponding side of an adjacent projection.

The foregoing specification signed at Louisville, Kentucky.

DONALD McDONALD.
